SECTIONAL PULL TOY

James H. Lavenson, Jenkintown, Pa., assignor to Wilkening Manufacturing Company, Philadelphia, Pa., a corporation of Delaware

Application May 28, 1957, Serial No. 46,380

Term of patent 3½ years

(Cl. D34—15)

Fig. 1.

Fig. 2.

Fig. 3.

Figure 1 is a side elevational view of a sectional pull toy showing my new design; the sectional pull toy being shown in relatively extended position as compared to Figure 2;

Figure 2 is a top plan view, but showing the sectional pull toy in relatively retracted position; and

Figure 3 is a front elevational view.

I claim:

The ornamental design for a sectional pull toy, as shown and described.
